BOTTLE CAP

George A. Buttress, Los Angeles, Calif., assignor
to Lonroy Corporation, Los Angeles, Calif., a
corporation of California

Application June 6, 1934, Serial No. 729,237

10 Claims. (Cl. 215—38)

This invention relates to a closure for milk bottles and the like and more particularly pertains to a cap for sealing the rim of a bottle mouth of the character set forth in my co-pending application for Letters Patent Serial Number 700,050, filed November 28, 1933, and also in my co-pending application for Letters Patent Serial Number 709,803 filed February 5, 1934.

An object of the invention is to provide a cap for covering the discharged end of a bottle in such manner as to protect the rim thereof against exposure during handling and transportation of the filled bottles, and thereby prevent pollution of the rim of the bottle mouth so as to avoid 15 possibility of contamination of the liquid content of the bottle on pouring such liquid over the rim.

Another object is to provide a bottle cap which is formed of sheet fibrous material and is substantially flat before application to a bottle, and 20 which is so formed that when positioned over the mouth of the bottle with the marginal portion of the cap protruding from the rim thereof such marginal portion may be readily bent downwardly around the bottle rim and be gathered into a 25 series of radially extending folds or webs and in a manner which will permit of the side portions of the individual folds being connected together.

Another object is to provide a construction in the sheet material of the cap for effecting 30 interconnection between the side portions of the individual folds in a fashion such that during application of the cap and effecting connection of the side portion of the folds the cap will be drawn tightly into contact with the neck of the bottle.

Another object is to provide a construction in which the connection between the side portions of the folds is so formed that on removing the cap from a bottle the connection will be mutilated or 35 altered in such manner as to afford a means of detecting unauthorized removal of the cap, so as to minimize the possibility of the contents of the bottle being tampered with without detection.

A further object is to provide a bottle cap of the above character in which the attachment of the bottle cap to a bottle is effected without the use of metallic fasteners and also without the use of cement or other adhesives.

With the foregoing objects in view, together with such other objects and advantages as may subsequently appear, the invention resides in the parts and in the combination, construction and arrangement of parts hereinafter described and claimed and illustrated by way of example in the accompanying drawing in which:

Fig. 1 is a top view of the cap as initially formed

from a sheet of fibrous material, such as paper;

Fig. 2 is a detail in section taken on the line 2—2 of Fig. 1 as seen in the direction indicated by the arrows;

Fig. 3 is a view in side elevation showing the cap as applied to a bottle;

Fig. 4 is a plan view of the cap depicted in Fig. 3.

Fig. 5 is a section taken on line 5—5 of Fig. 3.

Figs. 6, 7, 8 are fragmentary sections of the cap at line 5—5 of Fig. 4 showing the successive steps of folding the pleat securing means on application of the cap to the bottle.

Fig. 9 is a fragmentary view of the cap showing one pleat as it is after application to a bottle. 15

Referring to the drawing more specifically, A indicates generally a flexible sheet of fibrous material which is initially disk shaped and is preferably substantially circular in outline, being here shown as formed with a series of equally spaced 20 V-shaped notches 10 throughout its margin.

The sheet A is preferably formed of paper or pulp board of the character ordinarily used in milk bottle caps or closures, and is treated with paraffine or other suitable material whereby it is 25 rendered water resistant. The sheet is normally flat and is designed to be folded downwardly to extend around and over the rim of a bottle and to overlap the neck portion of the latter, and is preferably formed with an arrangement of fold 30 lines to facilitate its application to a bottle by bending the marginal portion of the sheet over the rim of the bottle mouth, then extending such marginal portion of the sheet alongside the neck of the bottle, that is around a substantially cylindrical body, and at the same time form a series 35 of folds or webs extending radially from the cap thus formed.

As here shown the sheet is formed with a circular fold line 11 disposed concentrically of the sheet and having a diameter substantially corresponding to the outside diameter of the bottle rim, and extending radially from the circular fold line is a series of fold lines 12 here shown as spaced 45 degrees apart and leading from the 45 circular fold line 11 to the apex of the V notches 10. Leading inwardly from the margin of the sheet on opposite sides of the radial fold lines 12 in inwardly inclined or diagonal relation to the latter, are short, straight fold lines 14 and 15, 50 and leading from the inner ends of the fold lines 14 and 15 are arcuate fold lines 16 and 17 which curve inwardly towards the fold lines 12 and terminate adjacent the inner ends of the latter contiguous the circular fold line 11. 55

5 The several fold lines are formed by either scoring or crimping the sheet and may be formed either during the course of applying the cap to a bottle by a mechanism employed for that purpose, or, may be formed previous thereto, as when initially constructing the sheet by forming it with punches and dies.

10 The area *a* encircled by the fold line *11* is designed to extend over the bottle mouth while the areas *b*, and the continuing areas *c*, extending between the adjacent fold lines *16-17* and *14-15* are designed to be extended downwardly over the rim of the bottle and around a contiguous portion of the cylindrical bottle neck *B*, 15 as particularly shown in Fig. 3, and the areas *d* and *e* extending between the radial fold lines *12* and the fold lines *14-16* and *15-17* respectively are designed to be folded to extend close together when the cap is applied to the bottle and when thus folded will provide a series of radially extending webs *18*, as particularly shown in Figs. 4 and 5 in which views the areas *d* and *e* are shown as brought into intimate contact with each other.

20 25 While any suitable number of such webs may be formed on the bottle cap it has been found in practice that a series of eight of such webs spaced 45 degrees apart is sufficient and highly satisfactory, but it will be understood, however, that the number of webs may be increased or diminished as occasion may require.

30 35 An important feature of the present invention resides in a construction whereby the contiguous side areas *d* and *e* of the webs may be securely connected together without the use of metallic fasteners or adhesives, and in a manner whereby in effecting connection between the side portions of the webs the cap will be drawn taut around the neck of the bottle and securely 40 retained in tight contact therewith. This is accomplished as here shown by forming the sheet *A* with rectangular openings *19* in the areas *c* with one margin of each of the openings extending adjacent a fold line *14* and its outer margin spaced a short distance from the margin of the sheet *A*, and its inner margin spaced a short 45 distance outwardly from the outer end of the fold line *16*. Punched from the area *c* is a tongue *20*, which tongue leads from the fold line *14* toward the opening *19* and has its outer end terminating a short distance from the latter, as particularly shown in Fig. 2. The tongue thus initially formed normally projects parallel with the plane of the sheet but is designed to be bent 50 rearwardly, as indicated by the dotted lines *f* in Figs. 2 and 6, and to be brought through an opening *19* on the opposite side of a web *18*, as shown in Fig. 7, and to have its outer end brought back through the overlying areas *d* and *e* of the web *18*, as shown in Fig. 5.

55 60 In thus connecting the tongue *20* with the side members of the web such side members are punctured by a suitable tool immediately before directing the tongue therethrough; the puncture being in the form of an elongated slot *21* extending longitudinally of the web as shown in Fig. 9.

65 70 The tongue *20* is formed of generally increasing width from the base thereof; its sides flaring outwardly as indicated at *g* and *h* to a point a little more than mid-way of the length of the tongue and the outer end portion of the tongue having its sides converging as indicated at *i* and *j* and terminating in a blunt rounded end. By thus forming the tongue and forming the slot *21* of 75 a length slightly less than the width of the tongue

at its widest point and then bending the tongue transversely as it is forced through the slot *21* the enlarged end portion of the tongue in protruding through the web *18* will act as a lock to tie the side members of the web together and will offer considerable resistance to withdrawing the tongue out of engagement with the web. 5

10 The base of the tongue being formed on the score line *14* and being comparatively narrow will be weakened to such extent that on prying the margins of the cap away from the bottle neck, as when removing the cap, the tongue will tear along the score line *14* before it can be withdrawn from the slot *21*, thus detaching the tongue and mutilating the cap in a fashion which will insure 15 against its being reapplied to the bottle without a noticeable disfigurement.

20 25 In the application and operation of the invention the sheets *A* are designed to be arranged in a stack within a magazine and to be ejected 30 therefrom and delivered to the tops of bottles to which they are to be affixed.

35 40 After the cap or sheet has been applied to the bottle top with the marginal portion of the cap protruding from the rim or mouth of the bottle 25 such marginal portion is forced downwardly to its position around the neck of the bottle by a suitable folding mechanism not necessary to be here shown, but which obviously involves means for bending the sheet along its fold lines. Coincident with the folding operation the tongues *20* are bent rearwardly and passed through the openings *19* and through the slots *21* in the fashion shown in Figs. 6, 7 and 8 and which operations are accomplished by a suitable mechanism adapted to effect connection of all the tongues *20* with the webs *18* simultaneously, so that the operation of threading the tongues through the webs will act to draw the marginal portion of the cap into intimate contact with 45 the outer periphery of the bottle neck thus securely fastening the cap in place.

50 55 As before stated to effect removal of the cap the latter is pried from the bottle by inserting a suitable tool between the lower marginal portion of the cap and the bottle neck and rupturing one or more of the tongues *20*, whereupon the cap by reason of its flexibility may be readily removed from the bottle.

I claim:

1. A bottle cap comprising a blank consisting of a sheet of fibrous material having a series of radial fold lines extending inwardly from the margin of the sheet, diagonal fold lines extending inwardly from the margin of the sheet on opposite sides of the radial fold lines having their inner ends terminating in spaced relation to the inner ends of the radial fold lines, and curved fold lines extending between the inner ends of said diagonal fold lines to the inner ends of the radial fold lines, said sheet being formed with openings adjacent the margin thereof disposed contiguous alternate diagonal fold lines, and tongues struck from said sheet extending from adjacent the other diagonal fold lines adapted to be passed through said openings on folding the sheet along said fold lines. 60 65

2. A bottle cap embodying a top wall and a flexible annular side wall formed of fibrous material, said annular side wall having a series of outwardly projecting webs including side walls extending adjacent each other, said annular side wall being formed with openings adjacent one side wall of each web, tongues struck from said annular side wall normally extending away from 70 75

the other side wall of each web, said tongues being bent rearwardly and extended over the bases of said webs and through said openings and having their outer ends threaded through the adjacent side walls of the webs.

5 3. A bottle cap comprising a top wall and an annular side wall formed in continuation thereof, said walls being formed of sheet fibrous material, a series of spaced radially and outwardly projecting webs on said annular side wall including side walls extending adjacent each other, and tongues struck from said annular side wall extending through and interconnecting the side walls of said webs.

10 4. A bottle cap comprising a top wall and an annular side wall formed in continuation thereof, said walls being formed of sheet fibrous material, a series of spaced radially and outwardly projecting webs on said annular side wall including side walls extending adjacent each other, and tongues struck from said annular side wall; said webs being formed with registering slots leading through the side walls thereof and said tongues being extended through said slots and interconnecting the side walls of the webs.

15 5. A bottle cap comprising a top wall and an annular side wall formed in continuation thereof, said walls being formed of sheet fibrous material, a series of spaced radially and outwardly projecting webs on said annular side wall including side walls extending adjacent each other, and tongues struck from said annular side wall; said webs being formed with registering slots leading through the side walls thereof, and said tongues being extended through said slots and interconnecting the side walls of the webs; said tongues having intermediate portions of a width exceeding the lengths of said slots adapted when the tongues are passed through said slots to project beyond the ends of the slots to resist withdrawing of said tongues.

20 6. A bottle cap comprising a top wall and an annular side wall formed in continuation thereof, said walls being formed of sheet fibrous material, a series of spaced radially and outwardly projecting webs on said annular side wall including side walls extending adjacent each other, and tongues struck from said annular side wall; said

25 webs being formed with registering slots leading through the side walls thereof, and said tongues being extended through said slots and interconnecting the side walls of the webs, said tongues being formed with intermediate portions of a width exceeding the lengths of said slots adapted when the tongues are passed through said slots to extend over the ends of the slots to resist withdrawing of said tongues; said tongues being weakened at the intersection with the annular side wall to facilitate their detachment therefrom.

7. In a bottle cap having a side wall, a series of radially and outwardly projecting webs on said side wall including walls extending adjacent each other, tongues formed on said cap leading across the inner margins of the walls of said webs, and means engaging the ends of said tongues to hold said webs against spreading.

8. In a bottle cap having a side wall, a series of spaced radially and outwardly projecting webs on said wall including said walls extending adjacent each other, and tongues formed on said cap leading across the inner margins of said webs and extending through and interconnecting the side walls of said webs.

25 9. In a bottle cap having a side wall, a series of spaced radially and outwardly projecting webs on said wall including side walls extending adjacent each other, tongues overlying the inner margins of said webs bent to fasten the inner margins of the side walls of the webs together; said webs being formed with registering slots leading through the side walls thereof to receive said tongues.

30 10. In a bottle cap having a side wall, a series of spaced radially and outwardly projecting webs on said wall including side walls extending adjacent each other, tongues overlying the inner margins of said webs bent to fasten the inner margins of the side walls of the webs together; said webs being formed with registering slots leading through the side walls thereof, said tongues being extended through said slots and interconnecting the side walls of the webs, and said tongues having portions projecting through said slots exceeding the lengths of said slots to resist withdrawing of said tongues.

35 40 45 GEORGE A. BUTTRESS.
